The ornamental design for a facial cleansing mitt, as shown and described.

DESCRIPTION

FIG. 1 is a front view of a facial cleansing mitt showing my new design;

FIG. 2 is a rear view thereof;

FIG. 3 is a right side view thereof;

FIG. 4 is a left side view thereof;

FIG. 5 is a bottom view thereof; and,

FIG. 6 is a top view thereof.

The cross-hatching in the figures is fragmentarily shown for convenience of illustration, it being understood that the cross-hatching is uniformly continuous over the surface on which it appears.
